United States Patent Office.

THOMAS SALEM LIVERMORE, OF LEICESTER, MASSACHUSETTS.

Letters Patent No. 79,239, dated June 23, 1868.

IMPROVED BELT-COUPING.

The Schedule referred to in these Letters Patent and making part of the same.

TO ALL WHOM IT MAY CONCERN:

Be it known that I, THOMAS SALEM LIVERMORE, of Leicester, in the county of Worcester, State of Massachusetts, have invented certain new and useful Improvements in Fastening Belts, called a Belt-Fastening or Coupling; and I do hereby declare the following to be a full, clear, and exact description of the same, due reference being had to the accompanying drawings, by the letters of reference marked thereon, in which—

Figure 1 shows my invention applied to a belt, and

Figure 2 shows the form of the coupling removed—

The same letters indicating the same parts in each.

My invention consists in the combination of a suitably-formed screw, having a conical or taper head, with a nut of similar make, as shown in fig. 2, the conical or taper part being of such form as to be drawn into the belt A, and leave the outside of both the head and nut smooth and lever with the surface of the belt, or nearly so. To apply it, the belt A is lapped, as shown in fig. 1, and holes made, and the screw B inserted from one side, and the conical nut c the other, and a few turns of the screw bring both its head and the nut in level, clasping and holding the belt firmly and strongly. If the point of the screw projects, it may be filed off smooth, and the ends of the belts may be scarfed, if preferred, and the nut may be made rough or square on its under side, if desirable, though usually not necessary.

My invention gives a ready means for adjusting the length of belts, being easily removed, and not liable to loosen by wear. It may also be used in place of rivets.

I am aware that it is common to make screws with conical heads, and that slightly-raised surfaces have been used for holding by compression; these I do not claim; but

What I claim as new, and desire to secure by Letters Patent, is—

The above-described coupling, consisting of the screw, with its conical head, in combination with a nut, of similar form, capable of being drawn into the belt, when constructed and operating in the manner and for the purposes above set forth and described.

T. S. LIVERMORE.
